G. W. PARKER AND W. F. PARKER, OF KALAMAZOO, MICHIGAN.

Letters Patent No. 77,085, dated April 21, 1868.

IMPROVEMENT IN FUR MUFFLERS.

The Schedule referred to in these Letters Patent and making part of the same.

TO ALL WHOM IT MAY CONCERN:

Be it known that we, G. W. PARKER and W. F. PARKER, of Kalamazoo, Kalamazoo county, State of Michigan, have invented certain new and useful Improvements in Fur Mufflers for gentlemen; and we do hereby declare that the following is a full, clear, and exact description of the same, reference being had to the annexed drawings, and to the letters of reference marked thereon making part of this specification, and in which—

Figure 1 is an inside view.

Figure 2 is a top view.

Figure 3 is a side view.

Figure 4 is a view of muffler on the head.

The nature of our invention consists in the manner of fastening the support or head-bands to fur mufflers, which renders the muffler more convenient, serviceable, and comfortable to the wearer, and easy of adjustment at all times.

It is well known that in the ordinary method of fastening a muffler upon the neck or over the coat-collar, by mere hooks and eyes in front, the top of the article sometimes becomes deranged by the hat or cap, and in very few cases only can the wearer prevent the muffler from dropping down in some measure, and thus expose the head between the hat and the muffler. In our invention this is prevented by the head-bands, which are securely fastened to the upper edges of the muffler, and can be properly adjusted, so that when the hat or cap is in its proper place, it will come closely down to the fur, and thus keep the air out from the head. In the old method, if the wearer should desire to loosen the front, either from being too warm, or from any other cause, the whole article must be removed; whereas, in our method, there is a great and decided advantage in the head-bands, because the front may be left entirely free, and yet the muffler will protect the back and sides of the head and the ears, which are more susceptible of cold than any other part, and thus the person can allow the throat and neck to be free, if desirable, as it is sometimes, or, if the front fastening should, by any accident, be broken, yet the muffler can be worn and protect the person. In horseback-riding this method of fastening is invaluable, because, should the rider have an unruly animal, requiring both hands to manage, and from exercise the rider be overheated, the front fastening may be loosened, and the head and ears be protected; whereas, in the old method, it will readily be seen the rider must either be closely muffled, and suffer from overheating, or release the muffler entirely, and have the cold air upon his head and ears.

In the drawings, A is the fur muffler, which is cut in such form as to protect entirely the neck and ears, and so meeting in front as to entirely protect the ears. The fur has a quilted lining, B, which may be made of silk or other suitable material. D D' are head-bands, which may be made of ribbon or other suitable material, and arranged at right angles to each other. These bands are so arranged that when the muffler is applied to the head, as shown in fig. 3, it will be found that the point of attachment of the ribbon or band D to the muffler, is immediately in front of the ears, while the band D' will be immediately above the centre of the neck.

The great advantage of our form of muffler, and the arrangement of the head-bands, will readily suggest itself to any one familiar with the ordinary straight fur muffler now in use. The bands keep the muffler always close to the neck and ears, possessing all the advantages of a hood, and still in no manner interferes with the hat or cap of the wearer.

Having thus fully described our invention, what we claim therein as new, is—

As a new article of manufacture, the fur muffler A, and lining B, when the same are constructed in the form shown, and provided with head-bands D D', and the whole is so constructed and arranged as to operate substantially as described and for the purpose specified.

In testimony whereof, we have signed our names to this specification in the presence of two subscribing witnesses.
